UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

STEERING-CHECK FOR AUTOMOBILES.

No. 838,832.

Specification of Letters Patent.

Patented Oct. 16, 1906.

Application filed May 23, 1905. Serial No. 261,655.

To all whom it may concern:

Be it known that I, HERMANN LEMP, a citizen of the United States, residing at Lynn, county of Essex, State of Massachusetts, have invented certain new and useful Improvements in Steering-Checks for Automobiles, of which the following is a specification.

This invention relates to automobiles having steering-gear operated by a hand-wheel, and its object is to provide a simple and effective hydraulic checking device for the same to prevent the transmission of steering-wheel strains to the hands of the operator.

The present invention relates to steering-gear in which there is a power-multiplying device between the hand-wheel and the steering-wheels and in which the hydraulic checking device is independent of the power-multiplying device. Such a scheme is broadly claimed in my pending application, Serial No. 188,848. In another application, Serial No. 261,144, I have shown such a system having a balanced valve for the checking device, said valve being moved lengthwise by a rod passing up through the steering-post to an auxiliary hand-wheel. In the present application I use this balanced valve and operate it by similar means; but the mechanism for transmitting power from the steering-post to the steering-wheels and the checking device for controlling the movement of the steering-post are specifically different and constitute the novelty herein. As in the last-mentioned application, the invention is especially applicable to high-speed cars, in which it is of the utmost importance that there shall be no play or lost motion in the steering-gear. The angular movements of the steering-post

are transmitted by chains and sector-sheaves to a rock-shaft which has one or more arms pivotally connected with a double-ended piston, or two connected pistons working in two cylinders filled with liquid and connected by a by-pass, which is controlled by the aforesaid balanced valve. Provision is made for taking up all slack, so that a rigidly-working set of connections is produced. The rock-shaft has an arm suitably connected with the steering-wheels, so that the angular movement of the steering-post will be communicated thereto.

In the accompanying drawings, Figure 1 is

a side elevation, partly in section, of my improved steering mechanism. Fig. 2 is a top plan view, with the steering-post and valve-rod cut off just above the checking device. Fig. 3 is a longitudinal section through the lower portion of the steering-post and valve-chamber. Fig. 4 is a longitudinal section through the hydraulic cylinders. Fig. 5 is a similar section on the line of the by-pass. Fig. 6 is a front elevation, and Fig. 7 is a cross-sectional elevation, through the cross-head of the pistons.

The steering-post 1 is tubular and carries at its upper end a hand-wheel 2. The post is rotatable in a bearing 3, which is preferably cast integral with the bracket 4, projecting from the cylinder 5. On said cylinder are inverted feet 6, by means of which the entire device can be secured to the frame or floor of an automobile. The outer half of the bearing 3 is removable, being held in place by bolts 7.

At suitable points on the steering-post, preferably adjacent to the ends of the bearing 3, are secured sheaves 8, to which are attached by the pins 9 one end of the chains or other flexible members 10. If chains are used, they are preferably of the universal type—that is to say, each block 11 has its two pins 12 placed at right angles with each other, so that the chain is as flexible in one direction as the other. The chains pass over sector-sheaves 13, and the end links have screw-threaded stems 14 passing through lugs 15 on said sector-sheaves and provided with adjusting-nuts 16 for taking up all slack. The sector-sheaves are clamped fast to a rock-shaft 17, mounted in a bearing 18 on the cylinder 5 and an outboard-bearing 19 projecting therefrom.

As the sector-sheaves are on opposite sides of the shaft, the chains must pass around the sheaves 8 in opposite directions so that when the steering-post is turned to wind up one chain it will pay out the other, the result being to rock the shaft 17 in one direction or the other. The shaft carries an arm 20, which is suitably connected with the steering-wheels, so that they can be controlled by the steering-post.

The hydraulic checking device comprises the cylinder 5, which has a longitudinal slot 21 in one or both sides for a portion of its

length, so that the only completely cylindrical portions are at the ends of the cylinder 5. In each of these portions is a piston 22, provided with cupped leather packing 23. 5 The pistons are rigidly connected, as by means of the sleeve 24, in which is a cross-head 25, forming a bearing for the wrist-pin 26, whose ends project through the slots 21, so that it can be connected, preferably, by 10 means of one or more pivoted connecting rods or links 27 with an arm or arms 28, rigidly secured to the rock-shaft 17 in a plane transverse to the axis of the cylinder. From this construction it follows that the oscillation of the rock-shaft by the steering-post will reciprocate the pistons in the cylinder.

The two ends of the cylinder are connected by a by-pass 29, preferably cored out or drilled in the wall of the cylinder. At some 15 point in its length the by-pass is provided with a controlling-valve. This is preferably located in a valve-chest 30, secured to the cylinder, said valve-chest being preferably a cylinder with its axis in line with that of the steering-post. In the inside of the valve-chest are two circumferential grooves 31, one 20 above the other and respectively connected with the adjacent ends of the by-pass. The valve has a cylindrical tubular body 32, provided with heads 33 of equal area. The valve-chest is filled with liquid, which passes freely through the tubular body of the valve, so that the pressure on its heads is balanced. The lower groove 31 opens into the space between 25 said heads, while the upper groove is normally closed by the upper head. When the valve is raised, the upper groove is uncovered so that the two grooves communicate and the liquid can pass freely from one 30 end of the cylinder to the other.

The valve can be lifted by a rod 34, which is fastened to its upper end and extends up through the tubular steering-post. The top of the rod is secured to the hub of an auxiliary hand-wheel 35, located, preferably, just below the main hand-wheel, the spokes of the auxiliary wheel passing through longitudinal slots in the hub of the main wheel. By 35 grasping the rims of both wheels they can be 40 squeezed together, thus lifting the rod and opening the valve. The adjacent faces of the wheel-rims are preferably flattened to permit them to fit together. A helical spring 36 encircles the valve-rod and abuts between 45 the valve and one or more stationary stops 37 inside the steering-post. This spring closes the valve when the auxiliary hand-wheel is let go.

With the valve closed the parts are locked 50 by the liquid in the cylinder which prevents the pistons from being moved. In high-speed cars the valve may be adjusted to allow a slight leakage, so that the main hand-wheel can be slowly moved to effect small 55 deviations from a straight course; but when a

decided turn is to be made the operator will involuntarily grasp the two rims tightly and by squeezing them together opens the valve, which unlocks the checking device and permits the steering-post to be freely rotated. 7

What I claim as new, and desire to secure by Letters Patent of the United States, is—

1. In a steering mechanism for vehicles, the combination with a steering-post, of flexible connections wound thereon in opposite directions, a steering-gear arm operated by said connections, and a hydraulic checking device connected with said arm. 7

2. In a steering mechanism for vehicles, the combination with a steering-post, of flexible connections wound thereon in opposite directions, a rock-shaft actuated by said connections, and a hydraulic checking device connected with said shaft. 8

3. In a steering mechanism for vehicles, the combination with a steering-post, of flexible connections wound thereon in opposite directions, a rock-shaft, sector-sheaves thereon to which said flexible connections are attached, and a hydraulic checking device connected with said shaft. 9

4. In a steering mechanism for vehicles, the combination with a steering-post, of flexible connections wound thereon in opposite directions, a rock-shaft, sector-sheaves thereon having lugs, screw-threaded ends on said flexible connections passing through said lugs, and adjusting-nuts on said ends. 9

5. In a steering mechanism for vehicles, the combination with a steering-post, of sheaves thereon, chains attached to said sheaves, a rock-shaft having its axis transverse to that of the steering-post, sector-sheaves on said shaft having said chains attached to them, an arm of the steering-gear on said shaft, and a hydraulic checking device connected with said shaft. 1

6. In a steering mechanism for vehicles, the combination with a cylinder, of a bearing thereon, a steering-post rotatable in said bearing, pistons in said cylinder, a rock-shaft connected with said pistons, and flexible connections between said rock-shaft and the steering-post. 1

7. In a steering mechanism for vehicles, the combination with two cylinders in line with each other, a piston in each cylinder, a rigid connection between said pistons, a rock-shaft connected with said pistons, a steering-post, and flexible connections between said post and shaft. 1

8. In a steering mechanism for vehicles, the combination with a cylinder having one or more longitudinal slots, of two connected pistons in the end portions of said cylinder, a rock-shaft having one or more arms connected with said pistons, a steering-post, and flexible connections between said post and rock-shaft. 1

9. In a steering mechanism for vehicles, 1

the combination with a cylinder having one or more slots along its middle portion, two pistons in the end portions of said cylinder, a sleeve connecting said pistons, a transverse wrist-pin in said sleeve projecting through said slots, a rock-shaft transverse to said cylinder and connected with said pin, a steering-post connected with said rock-shaft, and a valve controlling a by-pass connecting the ends of said cylinder.

10. In a steering mechanism for vehicles, a cylinder having longitudinal slots for a portion of its length, a bracket integral with said cylinder and carrying a bearing for a steering-

post, and bearings integral with said cylinder 15 for receiving a transverse rock-shaft.

11. In a steering mechanism for vehicles, a cylinder having an integral bracket carrying a bearing for a steering-post, and a valve-chamber secured to said cylinder in line with 20 said bearing.

In witness whereof I have hereunto set my hand this 20th day of May, 1905.

HERMANN LEMP.
